WINTHROP K. HOWE AND CHARLES S. BUSHNELL, OF ROCHESTER, NEW YORK, AS
SIGNORS TO GENERAL RAILWAY SIGNAL COMPANY, OF ROCHESTER, NEW YORK

TRACKWAY APPARATUS FOR TRAIN-CONTROL SYSTEMS

Original application filed July 26, 1923, Serial No. 653,898, now Patent No. 1,647,968, dated November 1, 1927. Divided and this application filed September 17, 1926. Serial No. 136,204.

This invention relates to automatic train control systems of the so-called continuous inductive control type, and more particularly to the trackway apparatus and control circuits for such a system.

5 This application is a division of our prior application Ser. No. 653,898, filed July 26, 1923, now Patent No. 1,647,968, dated November 1, 1927.

10 The primary object of the present invention is to provide trackway equipment and control circuits for train control systems of the continuous inductive type, which will permit the application of such system to railroads having blocks of different lengths, so that the system will be adequate for safety and at the same time suitable for facilitating train movement.

15 The accompanying drawing illustrates on two sheets, designated Fig. 1A and Fig. 1B, intended to be arranged end to end, specific embodiments of the invention to show its application to different length blocks, together with curves to facilitate explanation and understanding of the function and operation of this trackway apparatus and circuits.

20 The particular trackway equipment illustrated is intended for use with suitable car-carried speed control apparatus, such as shown in our prior application above mentioned. The significant characteristic of the

25 car-carried speed control apparatus, to be used in connection with the trackway equipment of this invention, is that it is governed or responds to three different indications or controls, corresponding respectively to a high or maximum speed limit, to a medium or intermediate speed limit, and to a low or minimum speed limit. For convenience in

30 explanation of the nature of the invention, it will be assumed hereinafter that this car-carried speed control apparatus is of the particular type shown in our prior application, in which two high and low speed cams

35 are provided, and in which gradually reducing or tapered speed limits are established by operation of the high cam from a high to a medium speed, and by the low cam from the medium speed to a low speed.

40 It requires a certain distance of travel,

ordinarily termed braking distance, for a train to reduce its running speed by a brake application, either from a high to a medium speed, or from a medium speed to a low speed.

45 If it is desired to have the medium speed limit, for example, effective at a given point along the track, it is necessary that the apparatus enforcing the speed reduction from the high speed to this medium speed, specifically the high speed cam, should be effec-

50 tive at a point in the rear of that given point at least as great as braking distance for the train for a change from such high to medium speeds. The same is true for a change from the medium to the low speed limit. In

55 other words there is a certain distance of travel required to run out the high speed cam from its initial high speed position to its low speed position, and a similar distance of travel is required to run down the low

60 speed cam from its initial medium speed position to its ultimate low speed position. The ideal length of block for such a speed control system is one in which the high speed cam can be initiated at the entrance end of

65 the block, and the low speed cam substantially at the point where the high speed cam reaches its run down or medium speed position, said low speed cam reaching its ultimate low speed position at the exit end of the

70 block.

75 In the practical application of speed control to railroads, particularly to those railroads already equipped with a block signal system, it is found that the length of the

80 blocks is different. The reasons for such different lengths of blocks vary. For instance, the location of the block signals for visibility sometimes fixes the location of the block ends in such a way that their length varies.

85 Other practical operating conditions, such as grades, low speed territory, and the like, require different length blocks.

90 These blocks encountered in practice may be either longer or shorter than the ideal block above mentioned. In case of a long block, if the high speed cam is started at the entrance end of that block, the train is required to reduce its speed sooner than necessary for

95 safety. On the other hand, for short blocks,

100

the high speed cam must be started at some point in the rear of the entrance to that block, at least braking distance from its exit end, otherwise the reduction in speed is not started soon enough for safety. In the case of very short blocks, approximately as long as the run down distance of the low speed cam, this cam may be used for the control throughout these short blocks. Situations may arise, however, where the desired block length will be somewhat longer than the run out distance of the low speed cam, but will be still less than the run out distance of both cams; and such a situation makes desirable a special arrangement of trackway circuits to provide the desired control at the proper point.

Referring to the accompanying drawing, it is assumed that the railway track will be divided by insulated joints into blocks in the usual way. Three blocks, U, V and W are shown, with the ends of adjacent blocks T and X. For convenience, corresponding parts associated with these different blocks are given the same reference characters with distinctive exponents. At the entrance to each block there is a signal Z, illustrated as a semaphore signal. The control circuits for such block signals may be of any well known type, and have not been shown. These signals assume clear, caution, and stop positions in the usual way, familiar to those skilled in the art. Operated by each signal are circuit controllers, as 242 and 237, which are shown conventionally, and which open and close contacts in different positions of the respective signal. The circuit controllers 242 and 237 close contacts from the clear or 90° position to the caution or 45° position, of the corresponding semaphore blade and other contacts in the stop or 0° position. The circuit controllers 448 and 449 close different contacts in the 90° and 45° positions. These circuit controllers 448 and 449 associated with the signal Z⁵ for the block U are also closed between the 0° and 45° positions. The circuit controllers 452 close a contact from 90° to 45°. The circuit controllers 466 and 467 of the signal Z⁵ close contacts in the 90°, 45° and 0° positions, the 90° and 0° contacts being connected by a jumper.

Each block is supplied with an interrail alternating current potential from the secondary of a transformer 230, said secondary being connected to the track rails by wires 233 and 234. The primary of this transformer 230 is connected to the secondary of a line transformer 235 through circuits controlled by the circuit controllers 242 and 237 of the corresponding signals so as to reverse the instantaneous polarity of this potential when the signal changes from its clear or caution position to its stop position. The line transformer 235 is energized from the transmission line 244 connected to a generator 245. The interrail potential thus provided causes cur-

rent to flow down one track rail and back through the other in a circuit conveniently called the loop or track phase circuit.

In each block connected across the track rails at selected points are balancing resistances 450, 451, and so forth. Alternating current is supplied to the middle points of these resistances by circuits hereinafter explained, so that current flows from one resistance down both track rails in multiple to an adjacent resistance. This circuit in which such current flows is conventionally termed the simplex or line phase circuit.

The currents in the track rails produced by these two loop and simplex circuits, suitably displaced in phase, are employed to cause operation of a three position car-carried relay (not shown), in a manner typical of the well known continuous inductive control type system, and familiar to those skilled in the art. This car-carried relay assumes one or the other of its energized positions, depending upon the relative instantaneous polarity of the currents in the loop and simplex circuits; and if either of these circuits is open, the relay assumes its de-energized position. Although it is the relative instantaneous polarities of the loop and simplex circuit currents which determine the operation of the car-carried relay, and in turn the speed limit effective, for simplicity and convenience these loop and simplex circuits will be referred to as independently having a relative normal or reverse polarity. If these two loop and simplex circuits both have a relative normal polarity, a clear or proceed indication will be given, establishing the high speed limit and maintaining inactive both the high and low speed cams. Likewise if both circuits are of a relative reverse polarity, the same is true. If either the loop or simplex circuit only is of the relative reverse polarity, the caution indication is transmitted, and the high speed cam is set into operation. If the simplex circuit current is cut off, the low speed cam is set into operation.

In the accompanying drawing, it has been attempted to illustrate certain assumed typical conditions of different block length, together with the particular control circuits required to provide the desired speed control for these different length blocks. Block U is representative of a block longer than the combined run out distance of the high and low speed cams, or in other words, longer than the braking distance for the normal speed running trains. The block V represents a block shorter than the run out distance of the two cams. Block W represents a still shorter block.

Above the track there has been shown on the drawing a series of permissive speed curves which represent the different speed limits established by the high and low speed cams. These curves are intended to corre-

spond approximately with the service braking distance of trains, so that by ordinary service brake applications, the running speed of the trains may be maintained below these speed limits, and also so that an automatic brake 5 application initiated at any point on these curves will bring the train safely to a stop before reaching the end of the corresponding block. The letters A and B, with exponents 10 corresponding to the blocks U, V and W, indicate the points along the track at which the high speed and low speed cams, respectively, 15 should be set into operation.

Referring now to the block U, the track-way equipment of this invention is organized 20 so that the change from a clear or proceed indication to a caution indication, which starts the high speed cam into operation, takes place at the point A^u at an intermediate point in the 25 block. To do this, special arrangements are made so that the polarity of the simplex circuit between the resistances 454 and 455 is reversed when the block U is a caution block and the signal Z³ assumes its caution position, this being necessary because, when the block 30 U is a caution block and the next block V in advance is occupied, the signal Z⁴ is in the stop position, and the relative polarity of the 35 loop circuit current for the block W is reversed by the circuit controllers 242 and 237 associated with the block V. The circuit connections by which this reversal of loop circuit current is obtained by operation of these circuit controllers can be readily traced on the 40 drawing, and need not be specifically described. By reversing the relative polarity of the simplex circuit current between the resistances 454 and 455, when the block U is a caution block, the car traveling in the first 45 part of this block up to the point A^u, picks up both loop and simplex circuit currents of relative reversed polarity, which of course produces the same effect on the car-carried relay as if these currents were of the relative normal polarity. Accordingly, the middle 50 points of the resistances 454 and 455 are connected to the circuit controllers 448 and 449 operated by the signal Z³, so that when this signal changes from its clear position to its caution or stop position, the relative polarity of these connections is reversed.

The simplex circuit current between the resistance 456 at the point A^u and the resistance 55 457 at the point B^u is supplied from the secondary of the transformer 246³, and has a fixed relative polarity.

From the point B^u to the end of the block, the simplex circuit current should be cut off, to start the low speed cam, when the block U 60 is a caution block. Since the block U is assumed, as shown, to be followed by a short block V, requiring a reversal of relative polarity of the simplex circuit current at the point A^u, even though the block U is a clear 65 block, at times when the block V is a caution

block, it is necessary to divide the portion of the trackway between point B^u and the end of block U into two sections, to provide the desired control, it being evident that this particular arrangement is not necessary if the block U were followed by a full length or a long block. Referring to the portion of track between the resistances 458 and 459, it can be seen that the simplex circuit current should be of the normal relative polarity when the block U is a clear block, that is, when the signal Z⁴ is in the clear or caution position, rather than the stop position; and that this current should be cut off when the block U is a caution block, and the signal Z⁴ is in the stop position. This control is provided by the operation of the circuit controller 452⁴ of the signal Z⁴. Referring now to the remaining section of the block U between the resistances 460 and 461, the simplex circuit current applied to this section should be of normal relative polarity when the block U is a clear block, of reverse relative polarity when the block V is a caution block, that is when signal Z⁴ indicates caution, and should be cut off when the block U is a caution block and the signal Z⁴ is in the stop position. This desired control is provided by the circuit controllers 448⁴ and 449⁴ of the signal Z⁴, contacts closed in the 90° and 45° positions of these circuit controllers being arranged to reverse relative polarity of the simplex circuit current.

Referring now to the block V, the arrangement of control circuits to provide for starting the high speed cam into operation at the point A^v in the block U when the block V is a caution block has already been pointed out. Between the entrance end of the block V and the point B^v, where the low speed cam should be set into operation, the simplex circuit current would normally be of fixed relation polarity, as in the case of the intermediate portion of the block U between the points A^u and B^u, except for the fact that, as shown, the block V is assumed to be followed by a very short block W which requires that the high speed cam be set into operation at the point A^w in the block V. Consequently, it is necessary to sub-divide the portion of the block V from the entrance end to the point B^v into two sections, the portion between the resistances 462 and 463 being supplied with simplex circuit current of fixed relative polarity from the transformer 246⁴, while the other portion, between the resistances 464 and 465, is supplied with simplex circuit current having its relative polarity specially controlled by the circuit controllers 466 and 467 operated by the signal Z⁷, so that the relative polarity of the simplex circuit current between these points is correct for the different conditions. If the block W is a caution block, and the signal Z⁵ is in the caution position, even though the block V is a clear block, the relative polar- 130

ity of the simplex circuit current between the resistances 464 and 465 should be reversed, so as to cause operation of the high speed cam at the point A^W . If the block W is occupied, and the signal Z^s is in the stop position, then the block V is a caution block, and the simplex circuit current between the resistances 464 and 465 should be of the normal relative polarity, since under these conditions the loop circuit current is reversed. Similarly, if both the blocks V and W are clear blocks, and the signal Z^s is in the clear position, then the simplex circuit current between the points 464 and 465 should be of the normal relative polarity. This desired control is provided by the circuit controllers 466 and 467, it being noted that these circuit controllers provide a normal relative polarity of simplex circuit current between the resistances 464 and 465 in the 90° and 0° positions of the signal Z^s , and a reversed relative polarity in the 45° position of this signal.

The portion of the block V from the point B^v to the end must also be subjected to control depending upon different conditions, in view of the assumed arrangement of a short block W following the block V. If the block W is occupied, and the signal Z^s is in the stop position, then the block V is a caution block, and the simplex circuit current between the resistances 468 and 469 should be cut off, to start the low speed cam at the point B^v . If the block W is a caution block, when the signal Z^s is in the caution position, the simplex circuit current between the resistances 468 and 469 should be reversed in relative polarity, even though the block V is a clear block, in order to maintain the high speed cam, started at the point A^W , in operation. If both the blocks W and V are clear, then the simplex circuit current between these two resistances should be of a relative normal polarity. This desired control is obtained by the circuit controllers 448^s and 449^s operated by the signal Z^s . In the 90° position of the signal Z^s , the simplex circuit current between the resistances 468 and 469 is of normal relative polarity, in the caution position of this signal, this simplex circuit current is of the reverse relative polarity, and in the stop position of this signal the simplex circuit current is cut off.

Referring now to the block W, this block illustrates the condition of a short block, in which the high speed cam should be set into operation at a point A^W in the block V in the rear, and also illustrates a case where the point B^w , where the low speed cam should be started if the block W is a caution block, happens to coincide with the point A^x , where the high speed cam should be started for proper control in a succeeding short block X, when said short block X is a caution block. The portion of the block W between the resistances 470 and 471 is supplied with simplex

circuit current with fixed relative polarity from the transformer 246^s. The portion of the block W between the points B^w and A^x and the exit end of the block is utilized to operate the low speed cam when the block W is a caution block, and the high speed cam, when the next block X is a caution block. This portion of the block W, therefore, requires a control the same as the portion of the block U between the resistances 460 and 461, and the same kind of circuit controllers 448^s and 449^s are employed.

If, as illustrated in our prior application above mentioned, the car-carried apparatus is arranged to require the engineer to make a special manipulation, termed acknowledgement, upon a change from clear to caution conditions, and from caution to stop conditions, it is desirable to provide suitable markers along the trackway to indicate the points A and B at which such acknowledgement is to be taken. Triangular signs C are used to designate the point A, and a disc D is used to designate the point B.

From the typical examples illustrated in the drawings, and the principles hereinbefore explained, other adaptations or modifications of the control circuits will be readily apparent which make it possible to apply a system of speed control to practically any particular length of block required. In this connection, it should be understood that the conditions of safety require that the speed limits shall be established at least braking distance from the point of required reduced speed and that conditions of facility of train operation make it expedient in some instances to delay establishing reduced speed limits and avoid train operation under reduced speeds unnecessary for safety. It should be understood that the particular sequence and arrangement of different blocks shown and described is merely representative or typical, and that various adaptations and modifications would be made in practicing the principles of the invention. Also it should be understood that the particular type of track way control circuits shown, including the control by circuit controllers operated by the signals, is likewise merely illustrative, and various modifications may be made without departing from the invention or the ideas of means underlying the same.

What we claim is:—

1. In an automatic train control system of the continuous inductive type in which currents of different controlling characteristics may be supplied to the track rails of the different portions of track to afford clear or caution indications, the combination with a block longer than the braking distance for the normal running speed of trains, of track-way means automatically controlled in accordance with traffic conditions for govern-

ing the supply of said currents to the track rails of said blocks to provide a clear indication throughout said block when the next block in advance is not occupied, said means
5 acting when the next block in advance is occupied to provide a clear indication between the entrance end of said block and an intermediate point therein at said braking distance from the exit end of the block and
10 a caution indication for an intermediate portion of said block in advance of said intermediate point.

2. In an automatic train control system as specified in claim 1, the combination with a block longer than the braking distance for the normal running speed of trains, traffic controlled means acting if the next block in advance of said long block is occupied to cut off the supply of current to the track rails
20 for a portion of said long block in the rear of its exit end.

3. In an automatic train control system as specified in claim 1, the combination with a block shorter than the braking distance for the normal running speed of trains immediately following a block longer than said braking distance, of trackway means operable to provide, when the block next in advance of the short block is occupied, a clear
25 indication in the long block from its entrance end to a point near its exit end at said braking distance from the exit end of the short block, and a caution indication throughout the remaining portion of said long block
30 in advance of said point, said means also providing a caution indication for a portion of the short block at its entrance end when the block in advance thereof is occupied.

4. In a train control system as specified in claim 1, a combination with a block shorter than the braking distance for the normal running speed of trains immediately following a block longer than said braking distance, of traffic controlled trackway means
40 acting when the block next in advance of the short block is occupied to cut off the supply of the current to the track rails of the short block for a portion of its length in the rear of its exit end.

50 In testimony whereof we hereby affix our signatures.

WINTHROP K. HOWE.
CHARLES S. BUSHNELL.
